TOY PISTOL

Joseph Yates, Salt Lake City, Utah

Application January 13, 1936, Serial No. 58,879

2 Claims. (Cl. 124—26)

My invention relates to toy guns, and has for its object to provide a toy gun for children which will shoot a perforate projectile at any desired target.

5 A further object is to provide a toy gun and projectile which will be compact, easily built, easily played with, and which projectile will be provided with a colored streamer to make it easier to find.

10 A further object is to provide a small compact powerful toy gun which will be highly efficient, cheap to manufacture, and of such simplified construction as to make it have a long life in the hands of a rough child.

15 These objects I accomplish with the device illustrated in the accompanying drawing in which similar numerals and letters of reference indicate like parts throughout the several views and as described in the specification forming a part of this application and pointed out in the appended claims.

20 In the drawing in which I have shown my toy gun,

Figure 1 is a side elevation.

25 Figure 2 is a side elevation of the gun with the power spring compressed showing the projectile ready for discharge.

Figure 3 is a plan view of Figure 2, with the projectile removed.

30 Figure 4 is an end view of the gun from the discharge or muzzle end.

Figure 5 is a side view of a modified spring compression or cocking device.

35 In the drawing I have shown the handle of the gun to represent an automatic pistol handle A, with a barrel or shaft 5, made of a rod inserted into the flat face 6, of the handle A. A trigger 9 is provided made of two ends 7 and 8 inserted into the lower front side of the handle

40 A. The top portion of the trigger 9 is made semi-circular with the top curved section adapted to engage over the rear end loop 15 of the spring compression saddle member 13. The spring compression saddle member 13 is made with two 45 spaced apart loop members 14 and 15 projecting thereabove at each end thereof joined together by a single bar along the lower side.

These loops are slidable on the barrel shaft 10 and a power spring 12 is coiled around the shaft 5 between the end loop 14 and a stop loop 10. The stop loop 10 is made by securing two ends 11 of a wire to the handle A and having the medial portion encircle the shaft 5 sufficient distance ahead of the trigger 9 to allow for compression of the spring 12 between the stop loop

10 and the end loop 14 and to allow the rear end loop 15 to pass under and be engaged by the curved or semi-circular portion of the trigger 9 compressing the spring and cocking the gun ready for shooting. To release the spring and fire the gun the ends 7 are compressed by the child against the handle. This raises the trigger 9 from the rear end loop 15 and allows the compressed spring 12 to expand suddenly throwing the projectile from the end of the shaft 5 10 with great force.

The projectile for the device shown as B is made similar in form to a large bead with a hollow or central bore therethrough to fit the shaft 5. Depending from said bead I provide a 15 streamer formed of a thin member 1 and a thicker member 2 said streamer to fly through the air with the projectile and enable the shooter to see where the projectile is going and to find it after it has hit the object and fallen to the 20 ground.

In Figure 5 I have shown a modified spring compression member as D with a loop 14' on one end thereof and a like loop 15' on the other end similar to the loops 14 and 15 of the member 13. 25

Depending from the bottom side of the frame I provide a cocking handle D1 which may be grasped by the child and used to pull back on the frame D to compress the spring 12 until the loop 15' engages under the trigger 9 at which 30 time the spring is ready for use again.

Having thus described my invention I desire to secure by Letters Patent and claim:

1. In a toy gun of the class described, the combination of a handle; a shaft fitted into the 35 end of the handle to act as the gun barrel; a trigger secured to the handle having the top end extended up and around the top of the shaft in a semicircular loop; a spring compression stop having a loop surrounding the shaft against 40 which loop the compression spring is engaged when cocking the gun, said loop being supported by wires secured into the sides of the handle; a spring compression member carried on said shaft with the ends of the spring formed in loops surrounding the shaft, one loop inside the compression stop and the other loop outside the stop, said inner loop to be engaged under the trigger when the spring is compressed for firing; and a compression spring carried between the stop and 45 the outside loop of the compression member.

2. In a toy gun for shooting projectiles, the combination with a handle of a shaft extended forwardly from the top end thereof to act as the gun barrel; a compression spring carried on 50

said shaft; a spring stop extended forwardly from said handle with a loop in the forward end against which the compression spring is compressed; a spring compression saddle member carried on said shaft having spaced apart loops encircling said shaft with one loop in front of said spring and the other loop back of said stop;

a trigger mounted to said handle near the lower end thereof with the body of the trigger extending up the handle with a curved portion at the top end to engage over the top of the rear loop of the spring compression saddle member to hold the spring compressed. 5

JOSEPH YATES.
